REFRIGERATOR CONSTRUCTION

Carl J. Wagner, Detroit, Mich.

Application March 15, 1948, Serial No. 14,826

1 Claim. (Cl. 62—89)

1

The present invention relates to a refrigerator and more particularly to a combination ice and mechanical refrigerator designed primarily for use in house trailers.

It is an object of the present invention to provide a combined ice and mechanical refrigerator including a transverse partition provided in the box at an angle so as to effect circulation of air within the interior of the box.

It is a further object of the present invention to provide a combined ice and mechanical refrigerator including an evaporator adjacent an upper corner of the box and occupying substantially less than the transverse half of the box, in combination with an air controlling partition extending transversely of the box and inclined downwardly and away from the side of the box at which the evaporator is located, so as to cause a continuous lateral displacement of air as it is circulated within the box by the partition.

It is a further object of the present invention to provide an ice-supporting tray of novel design.

It is a further object of the present invention to provide, in a combined ice and mechanical refrigerator, an ice-supporting tray extending transversely across the box immediately below an evaporator, the tray being provided with means to prevent damage to the evaporator as a result of shifting of a block of ice on the tray due to motion of the refrigerator.

It is a further object of the present invention to provide a tray-supporting bracket having a bumper element formed integrally thereon to prevent damage to the box as a result of shifting of ice therein due to motion of the refrigerator.

Other objects and features of the invention will become apparent as the description proceeds, especially when taken in conjunction with the accompanying drawings, wherein:

Figure 1 is a front elevation of the parts constituting the interior of my improved icebox;

Figure 2 is a section on the line 2—2, Figure 1;

Figure 3 is a side elevation, partly in section, of the parts constituting the interior of my improved refrigerator;

Figure 4 is an enlarged detail side elevation of the air distributing partition and the ice-supporting tray; and

Figure 5 is a section on the line 5—5, Figure 3.

Referring now to the drawings, the interior of the icebox is constituted by a lining member 10 of box-like form adjacent one upper corner of which is located an evaporator 11 which is connected to a suitable mechanical unit for supplying re-

2

frigerant thereto. It will be observed that the evaporator 11 occupies substantially less than half of the transverse width of the icebox. Directly beneath the evaporator 11 is an ice-supporting tray 12, details of which are shown in Figure 2. The tray comprises a wire border 13, preferably formed of a heavy wire and a plurality of longitudinally extending ice-supporting wires 14. It will be observed that the wires 14 are arranged in groups and in this instance each group of wires is made up of four separate wires. The groups of wires are separated by spaces substantially greater than the spacing between the individual wires of a separate group. By this construction a maximum amount of the under-surface of the block of ice 15 is exposed while at the same time adequate support is given to the block of ice so that the tendency for the ice to melt and to form depending icicles is substantially avoided.

Extending transversely across the tray 12 is an elevated bumper wire 16 which is so positioned as to prevent transverse shifting of the block of ice 15 into engagement with the evaporator. It will be recalled that the present refrigerator was designed primarily for use in a house trailer. Accordingly, when the trailer is in motion on the highway and when a block of ice such as shown at 15 is present, damage to the evaporator by the ice might otherwise be caused.

Referring now to Figure 3, there is illustrated an air controlling partition 20 which is inclined downwardly from the front to the back of the refrigerator and whose primary function is to cause a controlled circulation of air within the interior of the box. For this purpose the front edge 21 of the partition is spaced substantially inward from the front of the casing 10 (or from the door of the box) and the rear edge 22 of the partition is spaced forwardly from the back wall of the box. Air cooled by contact with the block of ice moves downwardly into contact with the partition and is directed rearwardly by it where it flows over the rear edge 22 into the lower portion of the box. Air warmed within the lower portion of the box raises and is directed forwardly in the box by the partition 20 where it passes around the forward edge 21 of the partition into the cooled space at the top of the box.

Since the evaporator unit is located at one side of the box and occupies substantially less than half of the transverse width of the box, there is a tendency for air cooled by the evaporator unit to circulate in a vertical plane at one side of the box. The present construction involves

means for directing this air laterally in the box so as to render the cooling effect of the air substantially uniform. For this purpose the upper surface of the partition 20 inclines downwardly away from the edge of the box in which the evaporator unit is located. The upper surface of the partition is indicated at 25 in Figure 1, and it will be observed in this figure that it inclines downwardly from right to left. This inclination of the air controlling partition also serves as a means for directing water from melting ice to a drain lip indicated at 26, whence the water flows into a drain outlet pipe 27. As a result of the transverse inclination of the upper surface 25 of the partition, a continuous displacement of air circulating in a vertical plane is provided, this displacement being to the left as seen in Figure 1, or in other words away from the side of the box in which the evaporator unit is located.

The air controlling partition 20 is shown in some detail in Figure 4 and comprises a lower pan-like element 30 and an upper closure 31. If desired, suitable insulating material may be provided between the elements 30 and 31. The sides of the pan 30 are provided with inwardly extending recesses 32, into which enters abutments 35 formed in the inner wall of the refrigerator. Thus the partition 20 may be readily removable merely by lifting it upwardly until the recesses 32 clear the inwardly extending projections 35. If desired, additional securing means, such for example as screws indicated at 36, may be provided.

The ice-supporting partition 12 rests at its forward edge on the elevated edge of the partition 20, as best seen in Figure 4. At its rear edge the ice-supporting partition rests upon a bracket 40 of particular design. The bracket 40 as illustrated in this figure is adapted to be secured to the inner lining of the refrigerator as by screws 41. It comprises a vertical portion 42 adapted to lie flat against the inner surface of the icebox. At its lower edge the bracket has a forwardly and downwardly inclined portion 43 which serves two functions. In the first place, the rear edge of the tray 12 rests upon this portion. In the second place, the portion extends inwardly a sufficient distance to overlie the rear edge of the partition 20 so as to form a drip guide for water formed by melting ice. Finally, at its upper edge the bracket 40 is provided with a forwardly and downwardly extending bumper portion 45 which is adapted to be engaged by a block of ice such as 15 if it is shifted laterally in the icebox due to motion of the vehicle. The bumper therefore prevents injury to the lining of the icebox.

Referring again to Figure 1, a folding shelf 50 is provided which occupies a portion of the space 51 in which the ice is received. The outer edge

of the pivoted shelf 50 is suspended as by a supporting arm 52. When it is desired to place a block of ice in the space 51 which substantially fills this space, the shelf 50 may be pivoted to its upper position as illustrated in dotted lines in this figure.

The air controlling partition 20, as best indicated in Figure 5, is made up of a pan-like lower member 60, and a cover-like upper member 61 having depending flanges 62 which fit over the upper edge of the lower member 60. The interior of the structure is provided with insulation as indicated at 63. This prevents the cold air above the partition 20 chilling its under surface, and thereby prevents condensation of moisture on the lower surface as warm air rises in the box, and also prevents cooling of warm air in the lower portion of the box, which would set up secondary air flow, and interfere with the smooth flow of cooled air downwardly at the rear of the box and warmed air upwardly at the front of the box.

While as previously stated the present refrigerator is designed primarily for use in house trailers, in which case it will be used as an electrical refrigerator when current is available and as an ice refrigerator when electric current is not available, the refrigerator may be equally useful in other applications, such for example as a built-in refrigerator in a house.

The drawings and the foregoing specification constitute a description of the improved refrigerator construction in such full, clear, concise and exact terms as to enable any person skilled in the art to practice the invention, the scope of which is indicated by the appended claim.

What I claim as my invention is:

In a refrigerator, a transverse longitudinally inclined partition having its ends spaced from the adjacent refrigerator walls and having recesses in its side edges, the inner side wall of said refrigerator being embossed inwardly to provide integral supporting abutments receivable in said recesses and holding said partition from endwise displacement.

CARL J. WAGNER.
